UNITED STATES PATENT OFFICE

166,032

GAS BURNER

Homer D. Du Fault, Easthampton, Mass., assignor
to Heatbath Appliances, Inc., Springfield, Mass.,
a corporation of Massachusetts

Application July 14, 1951, Serial No. 15,877

Term of patent 14 years

(Cl. D81—10)

To all whom it may concern:

Be it known that I, Homer D. Du Fault, a citizen of the United States, residing at Easthampton, in the county of Hampshire and Commonwealth of Massachusetts, have invented a new, original, and ornamental Design for a Gas Burner, of which the following is a specification, reference being had to the accompanying drawing, forming part hereof.

Fig. 1 is a top plan view of a gas burner, showing my new design;

Fig. 2 is a side elevational view;

Fig. 3 is an end elevational view thereof; and
Fig. 4 is an inverted plan view thereof.

I claim:

The ornamental design for a gas burner, as shown.

HOMER D. DU FAULT.
